DESIGN FOR A SHOE

Evelyn Ziniti, New York, N. Y.

Application October 13, 1945, Serial No. 122,814

Term of patent 7 years

(Cl. D7—7)

To all whom it may concern:

Be it known that I, Evelyn Ziniti, a citizen of the United States of America, residing in New York, county of New York, and State of New York, have invented a new, original, and ornamental Design for a Shoe, of which the following is a specification, reference being had to the accompanying drawing, forming part thereof.

The figure is a front perspective view of a shoe showing my new design. The opposite side

presents substantially the same appearance as the side shown.

My design for a shoe of the open-shank type is characterized by the solid vamp with a piping down the front of the same and a button under the fold visible from the front.

I claim:

The ornamental design for a shoe, substantially as shown and described.

EVELYN ZINITI.
